A circular seal or stamp. The top half contains the word "Inventor:" followed by the name "John A. Thommes". The bottom half contains the word "By:" followed by the name "Amos Thies". Below the name "Amos Thies" is the date "Oct 15, 1875". The entire text is in a cursive or script-like font. The seal is surrounded by a decorative border.

UNITED STATES PATENT OFFICE

2,183,415

POWER DRIVEN ROTARY TOOTH BRUSH
OR THE LIKE

John A. Thommes, Chicago, Ill.

Application May 5, 1937, Serial No. 140,781

5 Claims. (CL 15—28)

My invention relates to power driven brushes or the like, more particularly to electrically driven rotary instruments, such as tooth brushes or finger nail polishers, and has for an object 5 the provision of a simple, reliable, and inexpensive device of this character.

Power driven rotary brushes or the like for cleaning and polishing teeth, finger nails, etc., have heretofore been provided in which an electric motor is connected through suitable gears and flexible shafts to a rotatable brushing or polishing element. Such devices as heretofore constructed are rather limited in their application due to the fact that speed variations may be accomplished only by relatively intricate and cumbersome gearing arrangements, or by providing relatively expensive variable speed motors.

In the application of rotary brushes or similar instruments to the teeth, gums, or finger nails, injury of the teeth, etc., may accidentally occur due to improper manipulation of a positively driven instrument. Injuries of this character may be to a large extent eliminated by providing a slip drive between the brush and 25 the motor which effects positive drive of the brush only so long as the load on the brush is less than a predetermined value and which permits the slipping between the brush and the motor when an obstruction is encountered. It is, accordingly, a further object of my invention to provide a rotary power driven instrument of this character which is provided with slidable friction driving means, which is quickly and easily adjustable to provide varying speeds of 30 rotation in either of two directions, and which is simple and compact in its construction.

In carrying out my invention in one form, I provide a power driven tooth brush comprising a handle having a hollow head on one end and a drive shaft journaled in the handle for rotary and axial movement with respect thereto, one end of the drive shaft extending into the hollow head and carrying a driving member. One wall of the hollow head is provided with an aperture 45 in which is journaled a driven member for rotatably supporting a brush, which driven member is supported in frictional engagement with the driving member to provide a frictional driving connection therebetween, and means are provided for axially moving one of the frictionally engaging members to adjust the driving connection.

More particularly, I provide a driving motor connected through a flexible shaft to one end 50 of the drive shaft for rotating the same, and

the other end of the drive shaft which extends into the hollow head of the handle is provided with a driving wheel, the periphery of which carries a friction ring formed of rubber or similar material. The hollow head is provided with an open side in which is disposed a closure member for rotatably supporting a driven member, which comprises a disc having a flat face and a socket for detachably supporting a brushing element that extends outwardly from the closure 10 member. The friction ring on the driving wheel frictionally engages the flat roughened face of the disc-like driven member to provide a slip- 15 pable driving connection between the motor and the brush, and adjusting means are provided for 15 effecting relative axial movement between the handle and the drive shaft to move the driving wheel radially across the face of the disc so as to vary the speed and direction of rotation of 20 the brush. The engaging pressure between the driving and driven members may be controlled by adjusting the closure member so as to move the driven member axially toward or away from the periphery of the friction ring on the driving member.

For a more complete understanding of my invention, reference should now be had to the drawings in which:

Figure 1 is an elevational view of an electric tooth brush embodying my invention, certain portions being broken away in order more clearly to illustrate the constructional details;

Fig. 2 is an enlarged fragmentary sectional view of the device shown in Fig. 1;

Fig. 3 is a fragmentary enlarged sectional view of a modified form of rotary instrument embodying my invention;

Fig. 4 is a fragmentary sectional view of a still further embodiment of my invention; and

Figs. 5 to 10, inclusive, are detail views of 40 various massaging, polishing, or abrasive elements which may be utilized in place of the brushing element shown in Figs. 1 and 2.

Referring now to Fig. 1, I have shown my invention as applied to an electric tooth brush comprising a driven motor 10 which is preferably a constant speed motor of the type well known in the art and which is provided with a suitable tumbler switch 11 for controlling the energization of the motor, the external terminals of the motor being formed as prongs 12, so that the motor may be plugged directly into a wall socket, the prongs 12 forming both an electrical connection and a mechanical support for the motor. As will be more fully described 50

hereinafter, the motor shaft is connected to one end of a flexible shaft 13, which is of a type well known in the art and which is disposed within a flexible conduit or casing 14, and the opposite end of the flexible shaft 13 is connected to a drive shaft 15 journaled within a handle 16, the opposite end of the drive shaft 15 being drivingly connected to a brush element 17 which extends outwardly from one wall of a hollow head formed on the end of the handle 16. As will also be more fully described hereinafter, an adjustable coupling member 18 is provided for connecting the handle 16 to the flexible conduit or casing 14, and a cylindrical insulating bracket 19 serves to connect the conduit or casing 14 to the frame or casing of the motor 10.

Referring now to Fig. 2, in which I have shown what I now consider to be a preferred embodiment of my invention, it will be seen that the motor 10 includes a rotatable shaft 21 which is bifurcated or slotted to receive one end of a coupling member 22, the opposite end of which is connected in any suitable manner, preferably by brazing, to one end of the flexible shaft 13 which extends into a socket formed in the end of the member 22. As shown, the shaft 21 and the coupling member 22 are provided with co-operating apertures for receiving suitable screws 23, the shaft 21 and the screws 23 being insulated from the coupling member 22 by a pair of insulating plates 24 arranged on opposite sides of the member 22 and by a pair of cylindrical insulating members 25 which surround the screws 23.

Adjacent the other end of the flexible shaft 13, I provide a second coupling member 26, one end of which is provided with a socket into which the flexible shaft 13 extends, the other end of the coupling 26 being provided with a similar socket for receiving the extending end of the drive shaft 15, which is journaled for axial and rotary movement in a cylindrical bearing member 27 which extends substantially the length of the handle 16. As shown, the opposite end of the handle 16 is provided with a hollow head 28 which threadedly engages the handle 16, and the end of the drive shaft 15 which extends into the hollow head 28 is provided with a driven member or wheel 29 which carries on its periphery a friction ring 30, preferably formed of rubber or similar resilient material. Also supported in the hollow head 28 is a disc-like driven member 31, the upper flat face of which is arranged frictionally to engage the ring 30, the driven member 31 being rotatably journaled in a closure member 32 which is threaded, as shown, adjustably to engage co-operating threads in one wall of the closure member 28. In order to reduce to a minimum the friction between the driven member 31 and the closure member 32, I provide suitable anti-friction means, such for example as the ball bearing means 33 interposed between the upper face of the closure member 32 and a portion of the driven member 31.

As shown, the driven member 31 is provided with a downwardly extending cylindrical portion 34 which is journaled in an aperture 35 in the closure member 32, and this downwardly extending portion 34 is provided with a socket for receiving the shaft 36 of the brushing element 17. This shaft 36 is provided intermediate its ends with a ball-like spherical portion 37 adapted to be engaged by a plurality of spring fingers 38 which extend downwardly from the tubular portion 34 of the driven member 31. It will be un-

derstood, of course, that the spring fingers 38 are sufficiently resilient to spread whenever the shaft of the brushing element 17 is forced upwardly into the socket in the portion 34 and to positively grip the spherical portion 37 so as to hold the brushing element 17 in the position shown in Fig. 2. As will be explained more fully in connection with Fig. 7, the upper portion of the shaft 36 and the socket in the portion 34 of the driven element 31 are non-circular so as to prevent relative rotation between the driven member 31 and the brush, and so as to provide a driving connection therebetween.

It will be apparent now that when the shaft 15 is rotated, the frictional engagement of the ring 30 with the flat face of the driven member 31 effects rotation of the driven member 31 and the brushing element 17, and it will also be apparent that the speed at which the driven member 31 is rotated may be adjusted by moving the shaft 15 axially so as to move the ring 30 radially across the face of the driven member 31. Thus, when the ring 30 engages the driven member 31 adjacent its outer edge, a minimum speed of rotation of the driven member is obtained, and when the ring 30 engages the driven member 31 adjacent the center thereof, a maximum speed of rotation is obtained. Likewise, it will be apparent that if the ring 30 is moved across the center of the member 31, the direction of rotation of the driven member 31 will be reversed, and the speed of rotation in this reversed direction may be varied from a maximum to a minimum by moving the ring 30 toward the outer periphery of the driven member 31.

Since the driven member 31 is carried by the closure member 32 and the hollow head 28 which are, in turn, supported by the handle 16, and since the driving wheel 29 and its friction ring 30 are supported on the shaft 15, it will be evident that movement of the friction ring 30 across the driven member 31 may be accomplished simply by effecting relative axial movement between the handle 16 and the shaft 15.

In order to accomplish this relative axial movement between the shaft 15 and the handle 16, I provide the adjustable coupling means indicated by reference numeral 18 in Fig. 1. As shown in Fig. 2, this adjustable coupling means 18 constitutes a pair of cylindrical members 39 and 40, the member 39 being internally threaded, as shown, adjustably to engage co-operating threads on the handle 16 and externally threaded, as shown, to engage co-operating internal threads on the member 40. As will be more fully explained hereinafter, the co-operating members 39 and 40 are permanently connected together after assembly of the device by spinning down the left-hand edge of the member 40 tightly to engage the member 39, as indicated by the reference numeral 41.

As shown, the coupling member 26 is provided intermediate its ends with a portion 42 of enlarged diameter, and the member 39 is provided with an inwardly extending shoulder 43 arranged abuttingly to engage one side of the enlarged portion 42 so as to prevent axial movement of the shaft 15 relative to the members 39 and 40. Similarly, the member 40 is provided with an inwardly extending shoulder 44 which co-operates with the portion 42 of the coupling member 26 to prevent axial movement of the shaft 15 in the opposite direction relative to members 39 and 40. Adjacent its right-hand end the member 40 is provided with a pair of outwardly extending con-

centric ears 45 and 46 which are spaced apart radially to form a cylindrical socket onto which extends a sleeve 47 rigidly secured to one end of the conduit 14, which conduit surrounds the flexible shaft 13. In order to facilitate assembly of the device, the ear 45 is initially formed, as indicated by the broken lines, and after assembly of the sleeve 47 in the cylindrical socket between the ears 45 and 46, the ear 45 is spun inwardly so as to co-operate with the flange 48 on the end of the sleeve 47 permanently to position the sleeve 47 in the cylindrical socket while permitting rotation of the member 40 relative to the sleeve 47.

15 Adjacent its other end, the flexible conduit 14 is flanged, as shown, co-operatively to engage the cylindrical bracket 20 which is formed of insulating material and which may be secured to the frame of the motor 10 in any desired manner, as for example by the bolts 49.

It will now be apparent that by reason of the above described construction of the coupling means formed by the members 39 and 40, the coupling means, together with the handle 16, may 20 be rotated as a unit relative to the flexible conduit 14 and the drive shafts 13 and 15 so as to provide different angular positions of the brush 17 during a tooth brushing operation without varying the speed of rotation of the brush 17. Similarly, it will be apparent that simply by 25 rotating the coupling means comprising the members 39 and 40 relative to the handle 16, the handle 16, by reason of its threaded connection with the member 39, may be moved in a left- 30 hand direction from the extreme right-hand position shown in Fig. 2, and thus movement of the friction ring 30 across the flat face of the driven member 31 may be effected so as to vary the speed and the direction of rotation of the driven member 31. Likewise, the engaging pressure between 35 the friction ring 30 and the driven member 31 may be adjusted simply by rotating the closure member 32, the threaded connection between the hollow head 28 and the closure member 32 providing for inward and outward movement of the 40 closure member upon rotation thereof. In order to prevent accidental rotation of the closure member 32, I provide a suitable set screw 48, the innermost end of which is arranged to engage the closure member 32 so as to lock the closure member 50 in any desired position.

In addition to its compactness, simplicity, and ease of adjustment, a further advantage of my improved power driven instrument resides in its ease of assembly which may be carried out in the following manner. In order to assemble the various parts of the co-operating relation shown in Fig. 2, the drive shaft 15 is first inserted from the left-hand end of the cylindrical bearing 27 in the handle 16, and the member 39 is threaded onto the right-hand end of the handle 16. The coupling member 26, to which the flexible shaft 13 has already been secured, as by brazing, may then be secured to the extending end of the shaft 15, as for example by inserting a cross pin 50 into co-operating apertures in the coupling member 26 and the shaft 15, and the pin 50 may be permanently secured in the position shown by peening over or staking the edges of the aperture in the coupling member. The next step in the assembly of the device consists simply of threading the member 40 onto the member 39 and spinning the portions 41 of the member 40 inwardly so as permanently to engage the member 39, and the flexible conduit 14 may then be

slipped over the flexible shaft 13 so that the flange 48 on the sleeve 47 is disposed in the cylindrical socket in the right-hand end of the member 40, whereupon the cylindrical ear 45 may be spun inwardly to the position shown in Fig. 2. At this stage of the assembly it will be understood, of course, that the right-hand end of the flexible conduit 14 is not yet flanged and, accordingly, the cylindrical supporting bracket 20 may be slid over the right-hand end of the conduit 14 and moved far enough toward the left so that the conduit 14 and the flexible shaft 13 extend beyond the open end of the bracket 20.

The coupling member 22 may now be brazed to the extending end of the flexible shaft 13, the conduit 14 flanged as shown, and the connecting member 22 may then be secured to the shaft 21 of the motor, as for example by the screws 23. In order to complete the assembly, it is now only necessary to slide the bracket 20 in the right-hand direction until the inturned flanges thereon engage the outwardly turned flanges on the conduit, and it will be understood that the lengths of the various parts are so arranged that when these flanges engage, the outwardly flanged open end of the bracket 20 will engage the frame or casing of the motor 10 and may be secured thereto by the bolts 49.

Assembly of the head end of the brush may now be accomplished simply by threading the hollow head 28 onto the left-hand end of the handle 16 by positioning the driven member 31 and the ball bearings 33 on the closure member 32, and finally threading the closure member 32 into the open side of the hollow head 28. The device is now completely assembled, except for the brush element 17 which, as described above, may simply be inserted through the aperture in the closure member 32 and pressed into the socket in the downwardly extending portion 34 of the driven member 31.

In Fig. 3 I have shown a power driven rotary tooth brush provided with slippage friction driving means embodying my invention, the device here shown being adapted only for constant speed operation. As shown in Fig. 3, handle 51 of the device is provided with a hollow head 52 having an open side in which a closure member 53 is disposed, the hollow head 52 and the closure member 53 being provided with co-operating threads. The closure member 53 is similar to the closure member 32 described in connection with Fig. 1, in that it is provided with an aperture 54 and rotatably supports a driven member 55 which is arranged frictionally to engage a driving wheel 56 carried on the end of a drive shaft 57 which extends through, and is journaled in, a cylindrical bearing 58 in the handle 51. In this embodiment of my invention the driven member 55 supports a friction ring 59 formed of rubber or suitable resilient material, the periphery of which engages a substantially flat face of the driving wheel 56, and, if desired, this flat face of the driving wheel 56 may be serrated or otherwise roughened so as to increase the frictional engagement with the rubber ring 59. It will, of course, be understood that the flat face of the driven member 55 in the embodiment shown in Fig. 2 may be similarly serrated or roughened if desired. In this embodiment of my invention, relative axial movement between the shaft 57 and the handle 51 is utilized only to vary the frictional engaging pressure between the driving and driven members and, accordingly, a somewhat different type of coupling means is provided.

As shown, the coupling means here provided comprises a coupling member 61 which is internally threaded co-operatively to engage external threads on the right-hand end of the handle 51, 5 and the right-hand end of the coupling member is provided with spaced apart concentric ears 62 and 63 which are substantially identical with the ears 46 and 45 in the embodiment shown in Fig. 2, the ear 63 being adapted to be spun over, 10 as shown, in order to co-operatively engage a flange 64 on a sleeve 65 which is permanently secured to a flexible conduit or casing 66 surrounding a flexible drive shaft 67. It will, of course, be understood that the opposite ends of 15 the flexible shaft 67 and the conduit 66 are connected to the shaft of the electric motor in the identical manner described above in connection with Fig. 2. Intermediate the flexible shaft 67 and the drive shaft 51 I provide in this embodiment of my invention a coupling member 68 which is permanently secured, as by brazing, to the flexible shaft 67 and which is provided with a socket 69 shaped to receive a non-circular or 20 rectangular tongue 70 which extends outwardly 25 from the drive shaft 57. The coupling member 68 is provided, as shown, with a portion of enlarged diameter, one side of which is arranged adjacent an inwardly extending shoulder 71 on the coupling member 61, and a lock nut 72 is 30 provided which may be threaded into the coupling member 61 to a position adjacent the other side of the enlarged portion of the coupling member 68.

In assembling this embodiment of my invention, the flexible shaft 67 is first brazed to the coupling member 68 and then inserted into the coupling member 61 from the left-hand end thereof, whereupon the lock nut 72 and the handle 51 may be threaded into the coupling member 61 and the drive shaft 57 inserted from the left-hand end of the handle 51 and rotated until the non-circular tongue 70 engages the socket 69 in the end of the coupling member 68. The assembly of the flexible conduit 66 with respect to the coupling member 61 and the connection of the flexible shaft 67 to the motor may be carried out as described above in connection with Fig. 2, and the assembly may then be completed by threading the hollow head 52 onto the hollow handle 51 and inserting the driven member 55 and the closure member 53 in the hollow head.

In Fig. 3 the handle 51 is shown in the position to which it is initially threaded during assembly 55 of the device. In this position of the handle 51 sufficient clearance is left between the end of the tongue 70 and the bottom of the co-operating socket in the coupling member 68, as well as between the shoulder 73 on the driving wheel 56 60 and the flanged end of the bearing member 58, to permit axial movement of the shaft 57 with respect to the handle 51 so as to facilitate insertion of the driven member 55. After the driven member 55 has been inserted, the coupling 61 65 may be rotated so as to move the handle 51 in a right-hand direction and thereby cause the friction ring 59 on the driven member to engage tightly the flat face 60 of the driving wheel 56, the tongue 70 being thus urged into abutting engagement with the bottom of its co-operating socket.

In Fig. 4 I have shown a still further embodiment of my invention which is substantially identical with the embodiment shown in Fig. 3, 75 except that the handle 51 is provided with a

hollow head 74, the open side of which is disposed at a slight angle to the axis of the shaft 51 so that the closure member 75 and the driven member 76 supported thereby are disposed in other than perpendicular relation to the shaft 51. In this embodiment of my invention, the driven member 76 carries a friction ring 77, the outer periphery of which is tapered, as shown, so as to engage the serrated face 61 of the driving wheel 56. In some cases this angular relation 10 of the driven member, which of course carries the brushing element, may be found more satisfactory to the user of the instrument.

While I have described my invention thus far as particularly applied to a rotary tooth brush, 15 it will, of course, be apparent that various other working elements may be utilized in place of the brushing element 17 shown in Figs. 1 and 2. Thus, for example, a suction cup 78 of the type shown in Figs. 5, 6, and 7 may be substituted 20 for the brush 17, suction cups of this character being useful in massaging the gums. As shown, the suction cup 78 is provided with a non-circular or substantially rectangular shaft 79 and with a ball-like spherical portion 80 adapted to be engaged by the spring fingers 38 on the driven members 31 or 55 of Figs. 2 and 3, respectively. 25

Similarly, the brush 17 may be replaced by a polishing member 81 (Fig. 8) having a substantially hemispherical working surface 82 formed 30 of a material suitable for polishing finger nails, etc., or, if desired, rotary abrasive elements or files, such for example as the elements 83 and 84 shown in Figs. 9 and 10, respectively, may be utilized. The abrasive element 84 shown in Fig. 10 is provided with a peripheral groove 85, the bottom surface of which forms the abrasive working surface, the groove 85 serving as a guide 35 for finger nails or other members to be shaped or treated by the abrasive surface.

While I have shown particular embodiments 40 of my invention, it will be understood, of course, that I do not wish to be limited thereto since many modifications may be made, and I, therefore, contemplate by the appended claims to 45 cover any such modifications as fall within the true spirit and scope of my invention.

Having thus described my invention, what I claim and desire to secure by Letters Patent is:

1. In a power driven tooth brush or the like, 50 the combination of a handle having a hollow head on one end thereof, said hollow head having an aperture in one wall, a drive shaft journaled in said handle for rotary and axial movement with respect thereto, a handle retaining coupling 55 means journaled on said shaft in fixed axial relation thereto and adjustable relative to said handle to cause relative axial movement between said handle and said shaft, one end of said shaft extending into said hollow head, a driven member 60 journaled in said aperture for rotatably supporting a brush, a driving member fixed on said extending end of said shaft, said driven member comprising a wheel having a substantially flat face, an annular friction element carried by said driving member for peripherally engaging the flat face of said wheel to provide a frictional driving connection therebetween, and means for moving said driven member axially to adjust the engaging pressure between said annular element 65 and said face of said wheel.

2. In a power driven tooth brush or the like, 70 the combination of a handle having a hollow head on one end thereof, said hollow head being sufficiently small for insertion into the mouth 75

of a person using said brush and said hollow head having an aperture in one wall, a drive shaft journaled in said handle for rotary and axial movement with respect thereto, one end of 5 said shaft extending into said hollow head, a driven member journaled in said aperture for rotatably supporting a brush, a driving member fixed on said extending end of said shaft, said driven member comprising a wheel having a substantially flat face, said driving member peripherally engaging the flat face of said wheel to provide a frictional driving connection therebetween, and a handle retaining coupling means 10 adjustably engaging the end of said handle opposite from said hollow head, said coupling means being journaled on said shaft in fixed axial relation thereto and being adjustable relative to said handle to cause relative axial movement between said handle and said shaft to move said driving 15 member radially across said face of said driven member and thereby vary the speed of rotation of said brush.

3. In a power driven tooth brush or the like, the combination of a handle having a hollow head on one end thereof, said head having an open side, a drive shaft journaled in said handle for rotary and axial movement with respect thereto, one end of said shaft extending into 20 said hollow head, a driving member on said end of said shaft, a closure member for said open side having an aperture therethrough, a driven member journaled in said aperture and restrained from lateral movement therefrom and frictionally engaging said driving member, said 25 driven member being adapted for rotatably supporting a brush the working portion of which extends outwardly from said closure member, said closure member being adjustable into and out of said open side to vary the engaging pressure between said driving and driven members, and means on said handle for effecting axial 30 movement of said drive shaft to vary the relative position of said driving and driven members.

4. In a power driven tooth brush or the like, the combination of a handle having a hollow head on one end thereof, said head having an open side and being sufficiently small for insertion into the mouth of a person using said brush, a drive shaft journaled in said handle for rotary and axial movement with respect thereto, one end of said shaft extending into said hollow head, a driving member on said end of said shaft, a closure member for said open side having an 10 aperture therethrough, a driven member journaled in said aperture including a disc-like portion one face of which frictionally engages the periphery of said driving member, said driven member also including a shaft having a socket for supporting a brush the working portion of which extends outwardly from said closure member, and a handle retaining coupling means 15 adjustably engaging the end of said handle opposite from said hollow head, said coupling means being journaled on said shaft in fixed axial relation thereto and being adjustable relative to said handle to adjust said handle and said shaft axially with respect to each other to move said driving member radially across said disc and 20 thereby vary the speed of said brush.

5. In a power driven tooth brush, the combination with a handle having a rotatable drive shaft journaled therein, of a movable member cooperatively related to said shaft and said handle normally to prevent relative axial movement and movable by the operator to cause said movement, a driven member journaled in said handle, a variable speed transmission between said shaft and said driven member and responsive to said 25 relative axial movement to vary the speed of said driven member and manually movable adjusting means on said handle and accessible to the operator for effecting movement of said driven member laterally with respect to said shaft to 30 vary the driving characteristics of said transmission.

JOHN A. THOMMES.
